UNITED STATES PATENT OFFICE.

WAITMAN M. MORGAN, OF KANSAS CITY, MISSOURI.

ELEVATED CABLE RAILWAY.

SPECIFICATION forming part of Letters Patent No. 425,518, dated April 15, 1890.

Application filed December 26, 1888. Serial No. 294,730. (No model.)

To all whom it may concern:

Be it known that I, WAITMAN M. MORGAN, a citizen of the United States, and a resident of Kansas City, in the county of Jackson and State of Missouri, have invented certain new and useful Improvements in Elevated Cable Railways; and I do hereby declare that the following is a full, clear, and exact description of the invention, which will enable others skilled in the art to which it appertains to make and use the same, reference being had to the accompanying drawings, forming a part of this specification.

The object of my invention is, first, in a railway system of elevated tracks, to place alternately in track communication with diverging stationary main tracks at an angle to each other an intermediate elevated vibrating switch recoiling automatically to a position in one direction and vibrating in an opposite direction by the power communication from a traveling cable; second, to transmit the power of a traveling cable to successive elevated vibrating switches in communication with the main stationary diverging tracks from an automatically-recoiled position in one direction to an alternate position in an opposite direction; third, in an elevated vibrating switch interlocking with the main elevated track to enable the bolt-depressing lever to retard the traction-wheels of a vehicle on the switch until the switch is locked with the main track; fourth, to enable the locking-bolt on the main track to release the depressing-lever for the depressing of the bolt; fifth, in an elevated railway to enable the grade of a switch to assist the transit of the vehicle.

My invention further consists in the novel construction and combination of parts, which will be first fully described, and specifically pointed out in the claims.

In the drawings, Figure 1 is a view in perspective of an elevated cable railway, showing the diverging stationary main tracks supported upon single vertical columns in pairs and in line with each other in the plane of the tracks and in pairs at an angle to said tracks, and the intermediate vibrating switches recoiled in switch-connection with the main tracks in alternate direction and in power-

connection with the recoiling mechanism beneath the surface of the ground and in power-connection with the elevated traveling cable. Fig. 2 is a side elevation of the diverging main elevated tracks and an end elevation of switches seen from the side of the closed switch-tracks in Fig. 1, with the tracks broken away, showing the switch-shaft in power-connection with the cable-carrying shaft and the cable-sheaves and the clutch mechanism on the columns for reversing their position and the inclined tracks. Fig. 3 is a plan view of the elevated main tracks and switches as seen in Fig. 1, showing the switches vibrated in track communication with alternate stationary tracks when in power-connection with the cable. Fig. 4 is a detail view, partly in vertical section, of a portion of the vibrating hollow switch-shaft and the horizontal cable-sheaves thereon, showing the friction-clutch on the shaft against the under side portion of the upper sheave and the clutch-lever extending within the shaft and a portion of the vertical operating-lever. Fig. 5 represents in detail the interlocking mechanism on end portions of the switch-tracks and guide-tracks on the bridge-columns seen approaching each other to interlock, showing portions of the guide and main tracks of the switch which are in juxtaposition on opposite sides of a bridge-column and support the bolt-depressing levers, also the spring-actuated dog and bolt-socket and the elevated bolt and elevated lever on the bridge-column. Fig. 6 is a side elevation of the stationary tracks on the bridge and adjoining columns, showing the switch-closing mechanism on the guide-track and beneath the ground operated by the car in transit. Fig. 7 is a detail view, partly in vertical section, of a portion of one of the vibrating hollow switch-shafts, with the single pulley thereon, also in vertical section, showing the lever connected with the clutch upon the outside of the shaft. Fig. 8 is a detail view of the meeting end portions of the main and switch tracks, showing the spring-bolt and keeper for automatically locking the separate parts of the track.

Similar letters of reference indicate corresponding parts in all the figures.

In a former application made by me for

Letters Patent of the United States, filed in the United States Patent Office on the 7th day of September, 1888, Serial No. 284,808, I have described and shown an elevated-railway system in which stationary columns are arranged in series in a single line in a roadway and the tracks supported upon brackets projecting from opposite sides of the columns in opposite directions, and in the present application I have shown the stationary columns which support the main tracks, and placed in the roadway in a transverse relation in pairs at varying distances apart and said pairs arranged at an angle to the respective diverging tracks, and upon the said columns, which are denominated A A', the tracks, which are referred to in a former application supported upon a single column, diverge and extend at an angle to each other, as seen in the drawings.

In advance of the columns A A' and the proper supporting distance therefrom, and at an increased distance from each other to that of the columns A A', are erected the stationary bridge-columns A² A³, which extend in height above the said columns A A'.

The brackets B B on the respective columns A A² are placed a short distance below the relative horizontal plane of the brackets B' B' on the columns A' A³, and the bracket B on column A² is slightly lower in degree to that of the bracket B on the column A.

Upon one respective outer side portion of each column A A' A² A³, at a point on said columns at a proper height above the ground to support the horizontal main track and enable the suspension of a car therefrom, are attached the brackets B B'. The outer edges of the brackets B B' are made with vertical end portions b and in a transverse relation to the brackets B B', and in the upper portion is made a curved depression b'. To the vertical end portions b of the brackets B B' on the respective columns A A', at the highest point on said brackets and extending to a like point on the brackets B on the bridge-columns A² A³, are rigidly attached the terminals of the single continuous main diverging track-rails C C'. The rail C is inclined in the direction of said bridge-column A², and the ends c c of rails C C' on said bridge-columns extend a short distance beyond the brackets B B', for the purpose hereinafter described. Attached to the vertical end portion b of the brackets B B', a short distance below the tracks C C', are the guide-tracks D D'. The guide-track D is inclined in the direction of the bridge-column A² in the same degree as rail C, and said tracks D D' extend the corresponding length of the tracks C C', the end portions d d of which project beyond the bracket B on the bridge-column the corresponding distance of the portions c c of the tracks C C'. Attached to the side portions of the columns A A² and A' A³ a short distance beneath the brackets B B', and extending an equal distance in length to the tracks C and D, are the guide-

tracks E E'. The guide-track E is placed a short distance below the relative horizontal plane of the guide-track E' on columns A' A³ 70 and is inclined in a corresponding degree to the track E, and the end portions e e of the tracks E E' extend a like distance from the brackets B B' on the bridge-columns A² A³ to that of the portions c c and d d of the corresponding tracks C and D. Above the brackets B B' a suitable distance, and attached to the sides of the columns A A' A² A³ in a vertical direction to the guide-tracks E E', are the horizontal guide-tracks F F, the extreme 80 ends f f of which are halved and extend a corresponding distance beyond the brackets B B' on the bridge-columns A² A³ to that of the respective end portions c d e of the tracks C D E. The guide-track F is placed a short 85 distance below the relative plane of the guide-rail F' and is inclined toward the column A³ in a like degree to the rail C.

In the arrangement of the bridge-columns A² A³, which in pairs describe an angle to the 90 tracks, one of said bridge-columns is thereby advanced in the line of direction of the tracks and in the roadway a suitable distance relatively beyond that of the other column, and the ends of the respective tracks thereon are 95 also projected beyond the radius of the contiguous diverging tracks E D C F. In a direct line with the columns A' A³, and beyond the said column A³ a distance comparatively one-half of that described between said columns A' A³, is placed a vertical hollow vibrating switch-shaft G, which extends in height an equal distance to that of the bridge-column A² A³. Beneath the surface of the ground and the said shaft G is fixed a base 105 or bearing g, in the upper side of which is a socket g'. Upon the lower end portion of the shaft G, which also extends below the surface of the ground, is made a pivotal end portion g², which fits and vibrates within the socket g' 110 of the bearing g. Upon the upper end portion of the shaft G is a cap g³, which is perforated in a vertical relation, and through which extends a pivot g⁴ on the upper end of said shaft. To the side of cap g³ is attached 115 one end of the radial rods g⁵ g⁶, the opposite ends of which rods are attached, respectively, to the upper ends of the bridge-columns A² A³. On the side of the shaft G is fixed, at an equal height to that of the brackets B' on the 120 bridge-columns A³, one end of the switch-brackets G', the opposite end of which vibrates in the relative plane of the guide-track F and to within a proper distance therefrom. Upon the outer vibrating end portion of the 125 bracket G' is attached in a vertical relation a block g⁷, which extends the relative height of the guide-track D⁶ on the bridge-column A⁴ and in a downward direction to a point in the plane of the guide-track E on said bridge-column. Upon the opposite side of the shaft G, and extending in an opposite direction therefrom the distance described by the bracket G', is fixed at a corresponding height

the bracket G², upon the vibrating end portion of which is a post g⁷, similar in length to the post g⁶. In a transverse relation to and upon the respective vibrating end portions of the brackets G' G², and near the said ends, are attached the horizontal block-supporting brackets g⁸ g⁹, which extend from one corresponding side of each bracket G' G² a distance equal to that of the brackets B' B² on the bridge-columns A² A³, and are provided with like vertical end portions, as described, by the portion b of said bracket B. Upon the side of the shaft G in the plane of the guide-track F', and also above and in line with the bracket G' G², is attached the upper guide-track F², which extends radially to the end portion f of the track F' in one direction and an equal distance in an opposite direction, the opposite ends of which track are halved, so as to overlap the halved ends of the said track F'. To support the opposite ends of the said track F², a band g¹⁰ is placed around the shaft G above the track F², to which band, on opposite sides of shaft G, is attached one end of the respective rods g¹² g¹³, and the opposite ends of said rods are inclined in a downward direction and attached to the respective outwardly-extended ends of the track F². Upon the vertical end portions of the brackets g⁸ g⁹ on the brackets G' G² are attached in the plane of the tracks C' D' on the bridge-columns A³ the switch-tracks C² D², the length of said tracks corresponding to that of the guide-track F². Upon the lower end portion of the blocks g⁶ g⁷ on the end of brackets G' G² in a vertical relation to the guide-track F², and in the plane of the guide-track E' on column A³, is attached the guide-track E², the meeting ends of the tracks C² D² E² being halved, so as to overlap the halved ends of the tracks C' D' F', as described, which are in the radius of the said tracks C² D² F².

In advance of the bridge-column A² a distance comparatively one-half of that between the columns A' A², and in line with said column A² and the column A and a short distance in advance of the line drawn in a transverse relation through the column A³ and the main tracks E D' C F' thereon, is placed a hollow vibrating shaft H. Beneath the surface of the ground and the said shaft H is fixed a base or bearing h, in the upper end portion of which is a socket h'. Upon the lower end portion of the shaft H, which extends beneath the surface of the ground the depth required for the base h, is made a pivotal end portion h², which fits and vibrates within the socket h' of the bearing h. The upper end portion of the shaft H extends in height equal to that of the shaft G, and upon said end portion of shaft H is a perforated cap h³, through which extends a pivot h⁴ on the said end of said shaft. In the side of the cap h³ is secured one end of a stay-rod h⁵, the opposite end of which extends radially to and is secured in the side of the cap g³ on shaft

G. In the side of cap h³ is also secured one end of a stay-rod h⁶, the opposite end of which is attached to the upper end portion of the bridge-column A³. In the side of cap h³ is also secured one end of a stay-rod h⁷, the opposite end of which extends to and is secured to the upper end portion of the bridge-column A². Upon the upper end portion of the said column A² is attached one end of a stay-rod g⁸, the opposite end of which is extended to and is attached to the bridge-column A³. Upon the side portions of the shaft H, at an equal height to the bracket B on column A², is attached the horizontal vibrating bracket H', which extends radially from the side portions of said shaft in the direction of the said column A² and to within a short distance of said column, and upon the vibrating end portion of said bracket is attached in a vertical relation a block h⁸, which extends a short distance below and in line with the guide-track E on the column A² and in an upward direction in line with track F. On the opposite side of shaft H is attached at an equal height to the bracket H' the horizontal bracket H², which extends from said shaft in an opposite direction and an equal distance to that of H', and upon the vibrating end portion is attached in a vertical relation a block h⁹, the lower end of which extends downwardly a slight distance below that of the lower end of block h⁸ on the bracket H' and the upper end a slight distance below the relative height of the block h⁸. Upon the vibrating ends of the oppositely-extended brackets H' H², in a transverse relation to said brackets, and from the side of the blocks h⁸ h⁹ which corresponds to that of the column A², from which the brackets B project when said blocks h⁸ h⁹ are in line with the said columns A A², are attached the track-supporting brackets h¹⁰ h¹². The bracket h¹² is placed in the block h⁸ on bracket H' at the relative height of the bracket B in the column A² and extends outwardly a corresponding distance, and upon the bracket H² the bracket h¹⁰ is placed, slightly lower in position than the bracket h¹², and extends outwardly a corresponding distance thereto. To the upper ends of the blocks h⁸ h⁹ is attached in line with the track F a section of switch-guide track F⁴, one end of which is halved on its outer side, and said end extends radially from shaft H and meets the inner halved end f' of the guide-rail F. The opposite end of rail F⁴ extends in an opposite direction an equal distance, and is also halved and inclined slightly in position in the direction of the block h⁹. Upon the vertical end portions of the brackets h¹⁰ h¹², in line with the tracks C D, are attached the switch-tracks C⁴ D⁴, which are of equal length to that of the track F and are inclined in a corresponding degree. Beneath the brackets h¹⁰ h¹², and attached to the lower ends of the blocks h⁸ h⁹, is attached the lower switch guide-rail E⁴, which is similar in construction and length to the rail F⁴, and is

also inclined in a corresponding degree. The opposite meeting ends of the rails C⁴ D⁴ E⁴ are also halved in outward direction, those in line with the rails C D meeting and being retained in oppositely-halved end portions in said rails.

5 Nearly at an acute angle to the heretofore-described line of tracks C C', upon which the traction-wheels of a car are supported, and in a line radial to the opposite vibrating ends of the tracks C⁴ D⁴, which close in switch-connection with the ends of the said tracks C D, is placed in the roadway crossing a similar elevated stationary trackway to that heretofore described, the bridge-column A⁴ of which

10 is so placed in a vertical relation the proper distance radially from shaft H as to permit the ends of the tracks F⁵ C⁵ D⁵ E⁵ on column A⁴, which project a short distance therefrom and are halved in the direction of the said column, to meet the outwardly-halved vibrating ends of the tracks F⁴ C⁴ D⁴ E⁴ on the switch-shaft H, which, as heretofore described, are slightly lower than the opposite ends.

15 The bridge-column A⁵ is advanced in line beyond the position of the column A⁴ and the tracks F⁶ C⁶ D⁶ E⁶ thereon, and also said column occupies a corresponding position radially in relation to the shaft G that the column A³ does to the vibrating end portions

20 of the tracks F² C² D² E² on the said shaft. In a radial line of direction from the separate switch-shafts G H are placed the separate track-supporting columns A⁶ A⁷, which are placed the same distance apart as that of the

25 columns A A'. The bracket B on the column A is placed the corresponding height of the bracket h¹⁰ on shaft H, and the bracket B on the column A⁶ is placed slightly lower in degree than that of the bracket B' on the bridge-

30 column A⁴, and the guide-tracks E⁵ F⁵ on said columns A⁴ and tracks C⁵ D⁵ on the brackets on said columns are inclined therefrom in a degree corresponding to that of the tracks E⁴ C⁴ D⁴ F⁴ on the switch-shaft H.

35 To the side of the cap g³ on the shaft G is attached one end of the respective radial stay-rods g¹³ g¹⁴, the opposite end of which rod g¹³ is attached to the upper end portion of the column A⁵ and the opposite end of rod g¹⁴ to

40 the upper end portion of the column A⁴. To the side of the cap h³ is also attached one end of the respective radial stay-rods h¹³ h¹⁴. The opposite end of rod h¹³ is attached to the upper end portion of the column A⁵, and the

45 opposite end of rod h¹⁴ to the upper end portion of the column A⁴. The traction-power of the elevated road is afforded by means of an endless traveling cable, which is utilized in operating the switches and is supported as

50 follows: On the side of the brackets B B' on the columns A A', and between the vertical portion b of said brackets and the side of said columns, are attached the vertical sheaves i¹, which project a slight distance above the curved transverse depressions b' b' in said brackets. On the side of the bridge-column A², in the direction of the column A', and in

line with the sheave i, which is lower in position than the sheave i' on column A', is attached the sheave-bracket i^x, in which is mounted the horizontal sheave i², which is larger in proportion than sheave i'. On the side of the column A³, in the direction of the column A', and in a line horizontally with the sheave i³ on column A⁴, is attached the horizontal sheave-bracket i^x, in which is mounted the horizontal sheave i³, which is of the size of the sheave i².

55 On the side of the bracket B' on column A³, in the direction of A', is attached a vertical sheave i⁴, which is in line with the sheave i' on column A'. On the shaft G, above the brackets G' G² and in line with the sheave i³ on the column A³, is attached a horizontal sheave I, which is mounted on said shaft as follows: Around shaft G, which is shown square in form, is fitted a cylindrical flanged journal-bearing g¹⁵, between the flanges g¹⁶ g¹⁷ of which is journaled the horizontal sheave I. Through the side of the hollow shaft G and the bearing g¹⁵ below the flange g¹⁶ is inserted the bolt g¹⁸, which is provided with the nut g¹⁹. To the under side portion of the sheave I is rigidly attached a horizontal sheave I², the diameter of which sheave is nearly one-half of that of sheave I. Above the sheave I on shaft G and in line with the sheaves i' i³ on the columns A' A³ is journaled a sheave I³, which has an under concentric flat bearing-surface i⁰, and corresponds in diameter to the sheave I, and is mounted on shaft G as follows:

60 Around the hollow shaft G is fitted a cylindrical flanged journal-bearing g²⁰, upon the flange g²¹ of which the sheave I³ finds a bearing. (See Fig. 4.) Beneath the flange g²¹ and through the side of the bearing, and also through the opposite sides of the hollow shaft G, are inserted the securing-bolts g²², upon the outer ends of which are the nuts g²³. Around the shaft G and above the bearing g²⁰ is fitted a collar g²⁴, from the lower edge of which extends laterally a cylindrical flange g²⁵, which bears upon the journal-bearing g²⁰. Through the collar g²⁴, and also through the sides of the shaft G, are inserted the securing-bolts g²⁶, upon the outer end of which are the nuts g²⁷. On the side of the bracket B' on the bridge-column A⁵, in line with the sheave I³, is attached the sheave i⁵, and on the bracket B on column A⁴ is attached a similar sheave i⁶.

65 Upon the bridge-column A⁴, in line with the sheave I, is attached on the side in the direction of column A⁷ the horizontal sheave-bracket i^x, in which is mounted the horizontal sheave i⁷, and upon the column A⁵ in a line horizontal with the sheave i⁵, and upon the side toward the column A⁶, is attached the horizontal sheave-bracket i^x, in which is mounted the horizontal sheave i⁸.

70 The arrows indicate the direction in which the cable is traveling. One portion of an endless traveling cable, which is connected with the driving-power, is passed over the sheave

5⁶ on column A⁴, thence over sheave 5⁵ on column A⁴, thence around the loose sheave I³ on shaft G, and thence over sheave 5⁴ and 5⁵ on columns A³ A⁴ in one direction, and in opposite direction the opposite portion K' is passed over the sheave 5¹ on column A, thence over sheave 5², between the said sheaves and column A², thence in a transverse relation to the track C to and over sheaves 5³, and thence in a parallel relation to the portion K of the cable over the loose sheave I on shaft G, thence to the sheave 5⁷ on column A⁴, thence in a transverse relation to the track C⁶ to and over the sheave 5⁸ and between the said sheave and column A⁵, and thence in a parallel relation with the track C⁵ to and over the sheave on column A⁶. Upon the hollow shaft H, which is also square in form, is journaled upon a journal-bearing l, which is constructed and attached to shaft H in the same manner as the journal-bearing g¹⁵ to sheave I on shaft G, a sheave L, the diameter of which is equal to that of sheave I. Over the small sheave I² on shaft G is passed one end of a chain M, the opposite end of which is carried over the sheave L on shaft H and the two ends connected together, forming an endless chain.

For the purpose of vibrating the separate switch-shafts G H, and also the switch-tracks in the direction of the respective bridge-columns A² A³ and A⁴ A⁵, I employ mechanism in part as described in the former application referred to and operated by means of a suspended car in transit on the stationary main tracks. In the former application the vibration of the switch-tracks to and in line with the connecting main tracks is effected automatically from the main tracks by the cars approaching in opposite directions on diagonally-opposite tracks.

In the present application the switch is vibrated in track communication by the car in one direction only, the opposite movement being effected by the power communicated from the traveling cable. For this purpose on the columns A⁵ A⁷, and also on the columns A A², are attached on the sides which are opposite to each other, a short distance below the plane of the respective guide-tracks E E⁶, the horizontal sheave-brackets n n', and in said sheave-brackets are mounted the vertical sheaves n² n³. Beneath the surface of the ground, upon a suitable bed, and between the respective columns A A² A⁵ A⁷, a short distance from and in line with said columns, are fixed the vertical posts o o', which extend a short distance in height and are provided with the transverse slots o² o³. In the said slots o² o³ is placed the horizontal sliding bar o³. At a point intermediate between the opposite ends of the bar o³ is fixed a lug o⁴. On the bar o³, and on the side toward the column A⁷, is placed a sliding plate o⁵. Between the lug o⁴ and the sliding plate o⁵ and around bar o³ is a coiled spring o⁶. Beneath the surface of the ground in line with bar o³, and directly beneath the sheaves n² n³, are attached

to the respective columns supporting said sheaves the sheave-brackets n⁴ n⁵, in which are journaled the vertical sheaves n⁶ n⁷. 7c Upon the inner-side portion of the respective guide-tracks E E⁶ are attached the fixed depending slotted guides e' e². In said guides is placed a sliding bar o⁷. To the opposite sides of the guide e² are pivotally attached the upper ends of the depending levers o⁸ o⁹, the lower vibrating ends extending in a downward direction the proper distance for the contact with a suspended car. At a point intermediate between the opposite ends of the sliding bar o⁷, and upon opposite sides, are pivotally attached the upper ends of the rods o¹⁰ o¹², the lower ends of which extend to and are pivotally attached to the respective levers o⁸ o⁹ at a point between the vibrating end 85 portions of the said levers. In a transverse relation to the levers o⁸ o⁹, and rigidly attached to the vibrating end portions of said levers, is an operating-lever O, upon the end of which is a friction-roller o¹³, which meets 90 the car in transit and is operated thereby.

The car in my invention is suspended from the axle of the traction-wheels, which wheels are mounted on the respective tracks C C⁵, and upon the side of the car is a track inclined 95 in an upward direction from the lower portion of the front end to the upper portion of the rear end of said car, at which point it is made horizontal, and said track in the transit of the car meets the roller o¹³, and the lever O 100 is thrown forward and into an upward position, or from its normal position, as seen in dotted lines, into the position seen in full lines, Fig. 1, and the bar o⁷ is moved in a direction opposite to the movement described 105 by the car.

To one end of bar o⁷ is attached one end of a chain n⁸, which is passed over the sheave n³, thence in a downward direction between the said sheave and standard A², thence over sheave n⁷, and the opposite end attached to the end of bar o³ opposite said sheave. To the opposite end of the bar o⁷ is attached one end of a chain n⁹, which is first passed over the sheave n², thence in a downward direction 115 over sheave n⁶, and the opposite end attached to the end of bar o³ opposite said sheave. Upon the lower end portion of the shaft G, beneath the surface of the ground and in the plane of the bar o³, and relatively at 120 an acute angle to track C² above, is fixed rigidly a radial crank or arm g²⁸. To the vibrating end portion of the crank g²⁸ is pivotally attached one end of a bar g²⁹, the opposite end of which extends outside of and in the direction of column A⁴, and is pivotally connected 125 to the side of sliding plate o⁵ on rod o³.

Upon the shaft H, beneath the surface of the ground and in the plane with the bar o³, is attached a radial crank or arm h¹⁵, which 130 extends therefrom and vibrates in the angle described between shafts G and H and the bridge-column A³. To the vibrating end portion of the crank h¹⁵ is pivotally attached one

end of a bar h^{16} , which extends between the columns $A^2 A^3$ and is pivotally attached at its opposite end to the side of the sliding plate o^5 on the sliding bar o^3 between the said columns $A A^2$. As the bar o^7 is operated by the lever O , as heretofore described, the chain n^8 moves the bar o^3 in an opposite direction to the movement of bar o^7 , and the bar n^7 , connected with the arm g^{28} on the shaft G , operates to vibrate the said shaft and the switch-section on said shaft in track communication with the tracks $F^6 C^6 D^6 E^6$. In like manner the bar h^{16} , connected with the arm h^{15} on shaft H , is operated to vibrate the switch-section on said shaft in track communication with the tracks $F C D E$ on the columns $A A^2$.

For the purpose of vibrating the switch-shafts $G H$ and the respective tracks C^2 and C^4 thereon in the line of direction with and in track communication with the respective tracks C' and C , and in a direction contrary to that in which said switch-tracks are vibrated on the approach of a car, the rotary movement of the sheaves $I^3 L$ is communicated to the respective shafts $G H$ as follows: Upon the outer side portion of the shaft G , and beneath the lower flange of the journal-bearing g^{20} , is attached an arm g^{30} , which extends therefrom a short distance and in an upward curved direction. Upon the said arm g^{30} is pivoted a horizontal lever g^{31} , one end of which extends a short distance outwardly from the arm g^{30} , and upon said end of lever a friction-clutch g^{32} , which extends in an upward direction and bears upon the under side concentric bearing-surface i^0 of the sheave I^3 . The opposite end of the lever g^{31} extends through a suitable slot in the side of the shaft G (see Figs. 2 and 4) to a point intermediate between the inner opposite sides of said shaft, and to the vibrating end of said lever is pivotally attached the upper end of a rod g^{33} , the lower end of which rod extends in a downward direction. In the side of the shaft G , a short distance above the surface of the ground and upon the side which is relatively in the vertical plane of the guide-track E^3 , is made a longitudinal slot g^{34} . Upon the inside of the shaft G and opposite slot g^{34} is pivotally attached one end of a foot-lever g^{35} , which extends horizontally to the opposite side of said shaft through the slot g^{34} and a short distance beyond the outer side of the shaft G . The lower end of the vertical rod g^{33} is then attached to the lever g^{35} a short distance from its pivotal connection with the said shaft. Upon the shaft H is attached beneath the sheave L an arm l' , (see Figs. 2 and 7,) which is similar in construction to arm g^{30} on shaft G and extends a short distance from the said shaft, and upon said arm is pivotally attached a lever l^x . Upon the outer end portion of lever l^x is attached a friction-clutch l^2 , (see Fig. 2,) which bears upon the under side portion of the sheave L , the opposite end portion of which lever l^x extends to within a short distance of the side of shaft H , and

upon said end portion is attached the upper end portion of the vertical rod l^3 . (See Fig. 1.) Upon the side of shaft H to which is attached the guide-track E^4 , and an equal height to the lever g^{35} on the shaft G , is pivotally attached one end of a short foot-lever l^4 . The lower end portion of the rod l^3 is then attached to the lever l^4 a short distance from its pivotal connection with said shaft. When the outer end portion of the foot-lever l^4 is depressed, rod l^3 draws down one end of the lever l^x and elevates its opposite end, having friction-clutch l^2 , and the movement of the loose sheave L is communicated to shaft H , and the vibrating end of the switch on said shaft is thrown in track communication with the tracks $C^5 D^5$ on the bridge-column A^5 .

For the purpose of locking the switch at one vibrating end portion with the main stationary tracks a keeper p is attached to and upon the inner side of track E a short distance in rear of the halved end portion, and upon the inner side and end portion of the guide-track E^4 on the shaft H is attached an ordinary spring-bolt p' , the bolt of which engages with the keeper p on the track E . Near the opposite end of the switch and beneath shaft H and the bracket h^{10} , and pivoted at its lower end to the inner side of the track E^4 , is a lever p^2 , which is extended in a vertical relation a short distance above the guide-track D^4 and bent at right angles in the direction of said track, thence bent in a vertical relation close against the inner side of the track C^4 , its upper end projected a slight distance above said track.

To the lower end portion of the lever p^2 , a short distance above the plane of the track E^4 , is pivotally attached one end of a connecting-rod p^3 , the opposite end of which is connected with the spring-bolt p' on the opposite vibrating end of the switch-track. For the purpose of affording a safety-lock on the switch after the switch-track C^4 is vibrated in the operation of the foot-lever on the shaft H toward and in track communication with the stationary track C^5 on the bridge-column A^5 there is rigidly attached to the extended end portion e of the guide-rail E^5 a flat block e^3 , which extends the length of said extended portion and laterally across the side of the column A^5 . To the opposite side of the column A^5 , having the rail E^5 , and beneath the block e^3 , is attached a strip e^4 , which extends a like distance from said column and is in the same plane of the strip e . In the end portion of the strip e^4 the upper half a suitable distance from the end is cut away, leaving between the lower portion and the block e^3 a transverse opening e^5 . Upon the top portion of block e^3 is attached a narrow block e^6 , which extends the same distance from column A^5 as the portion e of rail E^5 and is narrower in width than said column. Near the end portion of the block e^6 , and through said portion, is made a vertical rectangular bolt-socket e^7 . In the socket e^7 is fitted a vertical

rectangular bolt R. Upon the side of bolt R, near the vertical end portion of the block e⁶ and near the upper end portion of the bolt R, is fitted a projecting pin r. In the opposite side portion of the bolt R is made a vertical slot r'. In slot r' and near the lower end portion of the bolt R is fitted a transverse pin r². In the upper side portion of the block e⁶ is made a longitudinal slot e⁸ of a suitable depth, which extends from the slot e⁷ to the column A⁵. Through the block e⁶, near the column A⁵ and in a transverse relation to slot e⁸, is inserted a pivot r³. Pivoted at its lower end portion to the pivot r³ is a lever R', and extending nearly at right angles from said lower end of the lever R' within the slot r' of bolt R and beneath the pin r² is an arm r⁴. The upper end portion of the lever R' is forked at r⁵ r⁶. Through the side of bracket B on the bridge-column A⁵ and the column A⁶, near the vertical end portion b, are made the transverse slots b³ b³. The opposite ends of a sliding bar S of the proper length to extend from the bracket B on column A⁵ to the bracket on column A⁶ are inserted in the slots b³ b³ in said brackets, one end of said bar extending to a point on the side of bracket B on column A⁵ above the lever R', and to said end is attached in a transverse relation one end of a transverse rod s, which extends in the direction of the vibrating forked ends r⁵ r⁶ of the lever R' (see Fig. 5) and between said forked ends and is provided with a head s'. On the bracket B on the column A⁶ and upon the side opposite to that facing the bracket B' on column A⁵ beneath the slot b³ is attached a lug s², to which is pivoted the lower end of a lever S', which extends in a vertical relation a short distance above the plane of the track-rail C⁵, and is bent at its upper end portion at s³. The lever S' is then pivotally attached at s⁴ to the side end portion of the sliding bar S, which extends through slot b³ in bracket B.

Upon the vibrating switch and upon the end portion of the guide-rail E⁴, which is vibrated toward and in contact with the guide-rail E⁵ on the column A⁵, is attached a horizontal flat plate T, which extends laterally from the upper side of said rail and in an outward direction a suitable distance therefrom, and is made the proper width to enter the slot e⁵ between the block e⁶ and the strip e⁴ on the column A⁵. An equal distance from the sides of the plate T is made, in a vertical relation through said plate, the rectangular slot t, which is slightly larger than the transverse dimensions of the bolt R. Upon the outer side portion of the guide-rail E⁴, and in the direction of the bracket h¹⁰, is attached at its lower end a short upright post u, the upper end of which extends to a height in line with the track D⁴. In the track D⁴ is pivoted one end of a rod u', which extends horizontally and in the direction of the post u and a short distance through said post. To the rod u' is attached near track D⁴ the lower end of a lever U, the upper end of which extends to and a short distance above the track-rail C⁴, and the extreme upper end of which lever is bent in curved relation at u². At a point between u² and the guide-rail D⁴ is attached one terminal portion of a coiled spring u³, the opposite terminal end of which spring is connected to the side of bracket h¹⁰. Upon the side of the guide-rail E⁴ and between post u and the plate T is attached one end of a narrow flat plate V, the upper end v' of which extends nearly the same distance in height as post u, and a short distance above the rail E⁴ is bent rearwardly a slight degree at an angle to its lower end portion in the direction of the guide-rail D⁴. Upon the upper end and outer side portion of said post v' is attached a coiled spring v³. To the plate V, and at the point on said plate from which the angle is given to the upper end v' of the plate V, is attached a lug v⁴. To the lug v⁴ is pivotally attached at its lower end the vibrating plate V', which extends in a vertical relation a short distance above the bent portion v', and to said plate V' is attached the coil-spring v³, against which said plate V' is given a bearing, as hereinafter described. Upon the outer side portion of the plate V', at a point in line horizontally with the end of the rod u' on the plate u, is cast a curved projection or lug v⁵. To the end portion of the rod u', which extends beyond the outer side of the post u, is attached rigidly one end of a short rod u³, which extends at right angles to rod u' across the face portion of the plate V' and rests normally upon the lug v⁵. Near the lug v⁵ the rod v³ is bent outwardly at right angles a short distance and the extreme end portion thence bent in the corresponding direction of the portion u³ and extends to a position relatively in a vertical line with the slot t in the plate T in the end of the guide-rail E⁴ on the switch.

The switch upon the shaft G and the bridge-columns which are thrown into track communication therewith are locked in precisely the same manner as hereinbefore described in that of the switch upon the shaft H and its bridge-column, the position of the locking parts being simply reversed for their application to said switch upon the shaft H.

In the operation of the elevated road and switches and in the position as seen in Fig. 1 the switch upon the vibrating shaft H is thrown in the forward and upward movement of the operating-lever O, which is arranged in the path of a suspended car, as heretofore described, on the track C, in line with the tracks F C D E on the columns A A², the spring-lock p' engaging automatically with the keeper p on the end of guide-track F, and the switch is secured from any movement. A car upon track C, it will be seen, which is operated by means of the traveling cable and its portion K', passes over the track C after operating the switch-operating lever O to a point a short distance beyond

and near the point where the cable departs from the line of the track C, and then drops the cable as a motive power, and in the gradual incline afforded by the tracks passes from track C to the track C⁴ on the switch and to a point where the wheels of the car strike the lever p², which lever unlocks the described end of the switch. The foot-lever l⁴ on the shaft N is then operated, which vibrates the shaft H and the opposite end of the switch-tracks to and in line with the tracks F⁵ C⁵ D⁵ E⁵ on the columns A⁵ A⁶. As the plate T on the end of the lower guide-rail E⁴ enters the slot e⁵ beneath the bolt R on the end of the guide-track E⁵ in column A⁵, the pin r strikes flatwise against the side of the plate v³ on plate V, which yields and releases the end u⁴ of the lever u³, which falls upon the upper end of the bolt R, and in the forward movement of the car on the switch to pass upon the track C⁵ on the bridge-column A⁵ the end u² of the lever U is depressed by the car-wheels, and the end u⁴ of the lever connected therewith depresses the bolt R into the slot t of plate T, which is brought opposite said bolt and locks the switch with the track C⁵ at the same time the end r⁴ of the lever R' is depressed, and the bar S slides forward in the direction of the vibrating shaft H as far as permitted by the forked ends of said lever R'. The car, following the gravity which the incline in the tracks permits, takes up the traveling cable and passes along the track C⁵ to the position of the lever S' and depresses the end s³ of said lever, which reverses the movement of the sliding bar S, and the bolt R is elevated and the switch is freed from engagement with the tracks on the bridge-column A⁵. Upon the return of the cars upon the track C⁶ the operating-lever O between the columns A⁴ A⁷ throws the switch upon the vibrating shaft G in track communication with the tracks on the bridge-column A⁴, which lock automatically in the same manner as the tracks upon the column A² are shown to engage with the switch on shaft H, the end of the bracket g⁷ swinging beneath the oppositely-traveling portions of K K' of the cable, and in passing to and upon the switch on shaft G the portion K of the cable is continuously held by the grip upon the car. The car being upon the switch upon shaft G, the foot-lever g³⁵ is operated to throw the clutch g³² against the sheave I³, and the opposite ends of the switch-tracks on shaft G vibrate toward the tracks F' C' D' E' on the bridge-column A³, and at the same time the mechanism which serves to reverse the movement between the columns A⁴ A⁷ is operated to bring the operating-lever O in a position in readiness for the succeeding car, which produces a reciprocal movement to that communicated by the traveling cable when the clutch is operated, the same results being apparent when the clutch is operated to reverse the movement of shaft H.

The locking of the ends of the tracks F² C² D² E³ on the switch with the tracks on the

bridge-column A³ is accomplished in the same manner as shown and described upon the switch on shaft H. In this manner the cars are switched from the main track upon the side tracks and parked or carried upon the diverging tracks as far as the extensions are made and reversed by means of a switch similar to that upon shaft G, placed at the end of the line and receiving the loop in the cable in the same manner.

For this improved elevated railway I employ a car suspended from and mounted upon the single track C and utilize the guide-tracks F D E as a means of preventing lateral vibration of the car, as fully shown and described in the former application alluded to, and in the employment of the cable system the means of switching the cars as herein described may be utilized in street-crossings or at the terminus of a line of track, from which point the cars are rapidly dispatched in opposite directions with more safety in the transit of street-cars than upon the ordinary surface roads.

Having fully described my invention, what I now claim as new, and desire to secure by Letters Patent, is—

1. In cable railways, the combination, with the sections of main track and a traveling cable, of an intermediate vibrating switch-shaft having a loose sheave in the loop of said cable, a vibrating switch on said shaft, a switch-closing lever connected with said main tracks and said switch, causing said switch to vibrate in an opposite direction to the movement of said cable, and a clutch on said shaft adapted to engage with said sheave on said vibrating shaft, for the purpose described. 95

2. In a cable railway, the combination, with the main tracks, of branch tracks at an angle to each other and vibrating switch-tracks having vibrating shafts and loosely-connected sheaves, an endless traveling cable having its opposite traveling portions looped around the sheaves upon one of said vibrating shafts, and power-conveyers upon the loose sheaves on one shaft and connected with the loose sheaves upon an adjoining shaft, and clutches upon said shafts adapted to engage with the loose sheaves, substantially as and for the purpose described. 110

3. In a cable-railway system of elevated tracks, a stationary main track consisting of diverging tracks and having terminal bridge-columns and an intersecting vibrating shaft and vibrating switch-tracks on said shaft in alternate track communication with said diverging tracks, said bridge-columns, an endless traveling cable on said main tracks, and a sheave loosely connected with and upon said shaft in the loop of said cable-retracting levers upon said stationary tracks in line of the movement of the said cable connected with said vibrating shaft and vibrating the switch-tracks in an opposite direction to the traveling movement of said cable, and a friction-clutch on said shaft engaging with one 120

of the said sheaves and reversing the movement of said shaft, as and for the purpose described.

4. In a cable-railway system of elevated tracks having suitable supporting-columns, a main track consisting of diverging stationary tracks at an angle to each other, having terminal bridge-columns, an intersecting vibrating shaft having braces connected with 5 said bridge-columns and a vibrating switch-track on said shaft, an endless traveling cable on said main tracks, and cable-diverting sheaves on said bridge-columns, and loosely-connected sheaves on said shaft in the loop 10 of said cable, supporting the oppositely-traveling portion of said cable, a friction-clutch on said shaft in contact with one of said sheaves and having an operating-lever, a retracting-lever on the main track, connected 15 with the said vibrating switch, and a self-locking catch on the said main tracks and the vibrating end of said switch, as and for the purpose described.
5. In elevated railways, a hollow rotary 20 switch-shaft having cable-sheaves loosely mounted thereon and a sheave-engaging friction-clutch and foot-lever extending within said hollow shaft and a connecting-lever, as shown and described.
6. In railways, the combination, with the 25 main track, of a vibrating switch-track in track communication, a coupling on the meeting ends of said main and said vibrating tracks in a normally-uncoupled position, and 30 a coupling-lever on the said switch-track, for the purpose described.

7. In railways, the combination, with the main track, of a vibrating switch-track in track communication, a coupling on said main 35 and at one end of said switch tracks in a normally-uncoupled position, a coupling-lever therefor, and a self-locking coupling at the opposite end of said switch-track, adapted to couple automatically with the main track, as 40 and for the purpose described.

8. In railways, the combination, with the main track, of a vibrating switch-track in track communication, a keeper upon one end of said vibrating switch-track, a lever on the main track and a bolt suspended thereon, a 50 sliding bar on said main track, connected with said bolt, and a bar-operating lever in the line of said main track, for the purpose described.

9. In railways, the combination, with the 55 main track, of a vibrating switch-track in track communication, a bolt-keeper on one end of said vibrating switch-track, a lever on the main track and a bolt provided with a pin suspended thereon, a bar on the main track, 60 having a bar-operating lever in the line of said track and connected with the bolt-carrying lever, a yielding plate on the switch-track, adapted to contact with the pin on the said bolt, and a bolt-depressing lever on the end 65 of said switch, provided with a rod supported by said yielding plate, for the purpose described.

10. In railways, the combination, with the main track, of a vibrating switch-track in 70 track communication, a bolt-keeper on one end of said vibrating switch-track, a lever on the main track and a bolt provided with a pin suspended thereon, a bar on the main track, having a bar-operating lever in the line of 75 said track and connected with the bolt-carrying lever, a yielding plate on the said switch-track, adapted to contact with the pin on the said bolt, and a bolt-depressing rod on the end of said switch, adapted to depress said 80 bolt and retained by the lug on said plate, a lever in the line of said switch-track, connected with said rod, and a spring connecting the said lever with the said track, for the purpose described.
